CLAIM

The ornamental design for a typeface as shown and described.

DESCRIPTION

FIGS. 1-3 depict an embodiment of a typeface showing the new design.

FIGS. 4-5 depict another embodiment of a typeface showing the new design.

FIGS. 6-8 depict another embodiment of a typeface showing the new design.

FIGS. 9-10 depict another embodiment of a typeface showing the new design.

FIGS. 11-14 depict another embodiment of a typeface showing the new design.

FIGS. 15-17 depict another embodiment of a typeface showing the new design.

FIGS. 18-21 depict another embodiment of a typeface showing the new design; and,

FIGS. 22-24 depict another embodiment of a typeface showing the new design.

FIG. 23

0 1 2 3 4 5

6 7 8 9 $ ¢
